ATTORNEY

UNITED STATES PATENT OFFICE.

CHARLES LAURENCE BURDICK, OF LONDON, ENGLAND.

PROCESS FOR PRODUCING DECORATIVE EFFECTS.

Original application filed March 5, 1926, Serial No. 92,623, and in Great Britain March 30, 1925. Divided and this application filed January 27, 1927. Serial No. 164,053.

My invention relates to a process for distributing liquids by compressed air for certain decorative effects, and to the product thereof, the present application being a 5 division of an application filed by me March 5, 1926, Serial No. 92,623.

Ordinary sprays which are used for distributing paints, colours, varnishes and the like are designed to produce a very complete 10 atomization completely covering the surface; the main object of my invention is to distribute liquids with little or no atomization and to produce lines or splashes, or both with regularity but without set design.

15 The viscosity of the liquid will to some extent determine the character of the results produced, but to ensure regularity (which is a very important factor for decorative effects) with any particular liquid, I have invented a new process whereby it is possible 20 to obtain peculiar decorative effects by spraying.

The main features of the apparatus especially designed to carry out this process 25 form the subject of my aforesaid application Serial No. 92,623. In the present process compressed air impinges from several directions upon a jet of somewhat viscous liquid in separate jets or zones of comparatively high velocity or pressure to draw it 30 out into lines and splashes, as opposed to the ordinary arrangements in which painting is accomplished evenly over a surface by dividing or atomizing the liquid as completely as possible.

The invention comprises the process and product which are described with reference to the accompanying drawings whereof the novel features or combinations are pointed out in the claims.

Referring to the accompanying drawings:—

Fig. 1 is an elevation of a preferred 45 form of apparatus suitable for carrying out the process in accordance with the invention,

Fig. 2 represents the appearance of a surface treated thereby, showing how the liquid falls upon the surface in strings and splashes.

Fig. 3 is a sectional elevation to an 50 enlarged scale of the nozzle arrangement.

Fig. 4 is a partial front elevation of the same, and

Figs. 5 and 6 are corresponding views of a modified form of nozzle.

The apparatus as shown comprises a handle 1 and a trigger 2 for controlling the supply of liquid and compressed air. The liquid is contained in a reservoir 3 supported upon a connecting pipe 4 through which it is fed to the liquid nozzle 5. Compressed air is supplied to the connection 6 and through the handle 1 and air supply passage 7. A branch pipe 8 leads from the passage 7 to a reducing valve 9 by means of which the air in the interior of the liquid reservoir is maintained at a predetermined or adjustable pressure. The cover 10 of the reservoir is suitably clamped down by screw 11, or the reservoir is otherwise made pressure-tight for this purpose. Alternatively 70 the pressure-feed of the liquid may be obtained by the head of liquid, the reservoir then being preferably fixed at a suitable height and flexibly connected to the apparatus. 75

For the control of the liquid at the delivery port or nozzle 5 I employ the usual pin valve 12 which would be manipulated by a lever, preferably the usual finger lever 2 designed to control both the air valve and 80 the pin valve.

The delivery port for the air, surrounds the liquid discharge port 5, but in place of the usual construction designed for only a narrow air passage around the liquid discharge port I provide a series of openings 13 so that the air will be divided up into a number of jets, which, impinging on the liquid from different radial points tend to draw out the liquid in lines and splashes. 85

It is very important, however, to secure a uniform current of air around the discharge tip, and to effect this I provide within the air cap or nozzle an equalizing compressed air chamber 14 and a series of inner outlets 95 from this, which delivers the air to the outer ports at a practically uniform pressure for each port all round the liquid discharge port.

Slight clearances 15, 15 where the nipple 16 and cap 17 are connected also assist in

pressure equalization and distribution of the compressed air at the outlet.

The separate jets emerging from the ori-
fices 13 all strike the liquid jet separately
5 or in a semi-merged condition only so as to
produce zones of air of comparatively high
pressure or velocity symmetrically arranged
around the liquid jet. The separate jet and
the only semi-merged jets are hereinafter
10 included in the term "air-pressure zones."

In certain cases the cap 17 may be ex-
tended so as to form an annular port 18 sur-
rounding the liquid delivery nozzle, but in
15 such a case the area of the port 18 must be
comparatively very large, as the separate air
jets must not be permitted or caused to merge
into a uniform annular jet, but must in all
cases remain as air-pressure zones.

The compressed air may be supplied to the
20 apparatus shown at a pressure in the neigh-
bourhood of 20 to 30 lbs. per square inch,
but the pressure in each case will of course
depend upon the design of the apparatus and
the nature of the liquid. Using a liquid of
25 the nature of a varnish paint, the reducing
valve 9 might be set to give a pressure in
the neighbourhood of 10 lbs. per square inch.
In operation the liquid emerging from the
30 nozzle is drawn out by the converging
streams of air into threads or strings which
fall upon the surface being treated with sur-
prisingly uniform decorative effect but in a
peculiar diversity of thickness and arrange-
ment as roughly indicated in Fig. 2.

35 The same surface may be treated first with
liquid of one colour and subsequently with a
different colour or different colours and a va-
riety of effects may thus be obtained for
many different purposes. It is to be under-
40 stood that the expression "air" includes all
suitable gases or gaseous mixtures.

The present application is limited to the
process and product claimed, the form of ap-
paratus illustrated and serving to carry out
45 the process forming the subject matter of co-
pending application Serial No. 92,623. In
using the apparatus shown or similar ap-
paratus, the operator swings the nozzle from
50 side to side moderately quickly at the same
time moving it down or along the surface to
be decorated, and very little practice indeed
is required to obtain sufficient uniformity in
the amount of decoration applied to each unit
55 of area. At the same time, there is no for-
mal pattern or repeat and there is thus no
tendency for the decoration to become mo-
notonous.

I claim:—

1. A process of producing decorative ef-
60 fects which consists in causing compressed
air delivered as independent jets to impinge
from numerous directions in air-pressure
zones upon a jet of somewhat viscous fluid
to draw and tear it out into threads and dis-
65 tribute it upon a surface.

2. A process of producing decorative ef-
fects which consists in causing compressed
air to impinge from numerous directions in
symmetrically arranged independent air-
70 pressure zones upon a jet of somewhat vis-
cous fluid to draw and tear it out into threads
and distribute it upon a surface.

3. A process of producing decorative ef-
fects which consists in causing compressed
air to impinge from numerous directions in
75 the form of separate jets upon a jet of some-
what viscous fluid pigment to draw and tear
it out into threads and distribute them upon
a surface in lines and splashes, and permit-
ting the pigment to harden upon the surface.
80

4. A process of producing decorative ef-
fects which consists in causing compressed
air to impinge from numerous directions in
symmetrically arranged separate jets upon a
85 jet of somewhat viscous fluid pigment to
draw and tear it out into threads and dis-
tribute them upon a surface in lines and
splashes, and permitting the pigment to
harden upon the surface.

In testimony whereof I affix my signature.
CHARLES LAURENCE BURDICK.
